UNITED STATES PATENT OFFICE

2,506,029

PULLING DEVICE

Abraham G. Maasdam, Kansas City, Mo.

Application January 28, 1947, Serial No. 724,878

4 Claims. (Cl. 254—164)

1

This invention relates to a pulling device and it is an object of the invention to provide a device or apparatus of this kind which can be employed to equal advantage as a wire stretcher, hoist, winch, load binder or in connection with such other operations where extreme pull is required to effect the desired result.

It is also an object of the invention to provide a device of this kind which can be operated in any position and which is especially advantageous in pulling operations such as drawing a stranded vehicle out of mud or sand, in pulling small stumps, and kindred work.

An additional object of the invention is to provide a device of this kind including a body carrying a winding drum, together with a lever for rotating the drum in a direction to wind a pulling cable thereon, with further means for the ready release of the lever from working engagement with the drum when it is desired to unwind the cable.

A still further object of the invention is to provide a device of this kind comprising a body carrying a winding drum for the pulling cable, together with a lever provided with a pawl for operative engagement with a winding drum to intermittently rotate the drum and wherein the body is provided with a pawl for coaction with the drum to normally hold the same against retrograde rotation and, furthermore, wherein means are provided to allow the simultaneous movement of both of the pawls into released position when it is desired to have the cable unwind from the drum.

The invention consists in the details of construction and in the combination and arrangement of the several parts of my improved device or apparatus whereby certain advantages are attained as will be hereinafter more fully set forth.

In order that my invention may be better understood, I will now proceed to describe the same with reference to the accompanying drawings, wherein:

Figure 1 is a view in perspective of the device or apparatus constructed in accordance with an embodiment of my invention;

Figure 2 is a view in top plan with a portion broken away;

Figure 3 is a view in side elevation;

Figure 4 is an enlarged fragmentary view partly in section and partly in side elevation illustrating in detail certain features of the device or apparatus as herein embodied; and

Figure 5 is a detailed view partly in section and

partly in elevation illustrating a slightly modified form of invention.

In the embodiment of the invention as illustrated in the accompanying drawings, B denotes 5 an elongated body of a skeleton type and which includes the side members 1 of desired length and substantially in parallelism, each of said members being of a length coextensive in length with the other. The opposite end portions of the members 1 are disposed outwardly in convergence as at 2 and 3. The outer meeting ends of the arms 2 are continued by the relatively short extension arms 4 in close contact one with the other. These short arms 4 are snugly received between the overlying sections 5 of a head H of desired size and configuration and the sections of the head 5 are maintained in assembled relation by the rivet 6 or the like disposed through the inner portions of said overlying sections 5 and through the short arms 4.

In swivel connection, as at 7, with the outer portion of the head H is an end portion of the shank 8 of a double swivel hook S. The head of the swivel hook is provided with the outstanding spaced short lugs 9 which constitute a clevis and through which is adapted to be inserted in a conventional manner a clevis pin 10.

The converging extremities of the arms 3 are also continued by the relatively short arms 11 in close contact one with the other and these short arms 3 are straddled by the side members 12 of a substantially U-shaped clip 14. These arms 12 are held to the arms 11 by a rivet 15 or the like which also provides means for mounting or holding the clevis shackle 16. This shackle 16 has coupled thereto, as at 17, in a conventional manner, a slip hook 18.

At substantially the longitudinal center of the body B the side members 1 have interposed therebetween and supported thereby a shaft 19 on which is mounted a winding drum D positioned between and substantially bridging the space between the members 1. This drum D at its ends is provided with the surrounding flanges 20 and 21, the flange 21 constituting a ratchet gear whereby the drum may be intermittently rotated in one direction to wind thereon the pulling cable C.

Freely and pivotally engaged with the shaft 19 between the side members 1 and the ends of the drum D are the elongated arms 22 which are arranged at one end of an operating lever L. The outer extremities of these arms 22 are continued by the inwardly converging arms 23. The arms 23 are continued by the elongated straight

arms 24 in close contact with each other and held in assembled relation by one or more rivets 25. The outer extremities of these arms 24 are disposed on a slight angle with respect to the inner portion of the arm 24 as indicated at 26 to provide a more convenient hand grasp to facilitate the desired swinging of the lever L and particularly when it is desired to rotate the drum D to wind the cable C thereon to effect the required pull.

The arms 22 closely adjacent to the arms 23 have interposed therebetween and supported thereby a shaft 27 on which is freely mounted the hub sleeve 28 for the elongated pawl 29 for coaction with the ratchet 21. As is particularly illustrated in Figure 3 of the drawings, this pawl 29 is normally in effective engagement with the ratchet 21 to lock the drum D against rotation in one direction but engaged therewith in a manner whereby swinging movement of the lever L in one direction will effect the desired rotation of the drum to wind the cable C thereon. The main purpose, of course, of this pawl 29 is to effect the rotation of the drum D.

The hub sleeve 28 has extending therefrom the upwardly and inwardly curved operating arm 30 of desired length and which has its outer or free extremity normally positioned outwardly of the lever L, as illustrated in Figure 3. Operatively engaged as at 31 with the inner portion of this arm 30 and one of the side arms 22 of the lever L, as at 32, is a torsion spring 33 which encircles the hub sleeve 28 of pawl 27. The outer end portion of this spring 33 is operatively engaged with an inwardly directed lug 34 carried by the arm 22.

The drum D is normally held against retrograde rotation by a second pawl 34. This pawl 34 is carried by an end portion of a hub sleeve 35 freely mounted on a shaft 36 bridging the space and supported by the arms 1 at a point closely adjacent to the arms 2 of the body B. This pawl 34 coacts with the ratchet flange 21 and is constantly urged into operative engagement with said ratchet flange by a torsion spring 37 anchored at one extremity as at 38 to a lug extending inwardly from one of the side members 1 of the body B while the opposite end of this torsion spring 37 is operatively engaged as at 39 with the pawl 34. While this pawl 34 holds the drum D against retrograde rotation, it is to be noted that it offers no hindrance or obstruction to the desired rotation of the drum upon working movement of the lever L.

When the pawl 29 is released from the ratchet drum by operation of the arm 30, and the lever L is swung substantially to the limit of its backward movement, the pawl 29 will engage and free pawl 34 into released position, thus allowing unhindered unwinding of the cable C from the drum D.

The sleeve 35 is provided with the operating lever or handle member 40 disposed on the same side of the body B as the lever L and which lever or handle member 40 permits a ready releasing movement to be imparted to the pawl 34.

The clip 14 provides a guide through which the cable C is disposed and the end portion of the cable C outwardly of this clip or guide 14 has attached thereto a clamp A. This outer extremity of the cable C has affixed thereto a head E provided with the outstanding spaced arms 42 between which is held by a cotter pin 43 or the like the outer end of an elongated rod 44. The inner or opposite end portion of this rod 44 is operatively engaged with an outstanding arm 45 of a

cam 46. This cam constitutes a clamping element which coacts with the flange 47 disposed along a marginal portion of an elongated body plate 48 of desired dimensions.

In advance of the cam 46 at the side remote from the flange 47, the plate 48 is provided with an inwardly disposed flange 49 through which the rod 44 is freely disposed and therefore maintained in substantially a fixed line of travel, although it is to be understood that the opening within this flange 49 is of sufficient diameter to allow such lateral movement of the rod 44 as may be required to allow the same to have unhampered movement as the cam 46 is swung into either active or inactive position.

It is believed to be readily apparent that in the use of the apparatus as herein embodied either as a wire stretcher, a bale carrier or for any other purpose, the strain imposed upon the cable C upon proper operation of the lever L will exert such pull upon the arm 45 of the cam to effectively maintain the said cam in tight clamping engagement with the strand passed between the working edge of the cam 46 and the flange 47. In other words, the greater the pull upon the cable C, the tighter the clamping action.

The cable C is of a performed wire rope of a type possessing a certain degree of inherent resiliency, yet sufficiently flexible to wind or unwind relative to the drum D. This is of advantage because when the pawls 29 and 34 are released from the drum D, the cable C will tend to automatically loosen itself on the drum D and the portion of the cable C within the confines of the body B will have a tendency to assume a straight position.

To minimize injury to the user and also, of course, to assure the maintenance of the cable C wound upon the drum D, a guard or fender G is provided. This guard or fender G comprises an elongated strip of metal of a width substantially equal to the width between the flanges 20 and 21 of the drum D and one end portion of this strip is anchored as at 50, to a cross member 51 fixed to the side arms 1 at a point preferably adjacent to the arms 3. This guard is disposed on proper radius around the drum D but spaced from the periphery thereof a distance sufficient to allow the desired winding of the cable C upon the drum.

It has been found advisable in a number of instances to employ the embodiment of the invention as illustrated in Figure 1 wherein is illustrated another means for attaching the flexible member or cable to the drum. In the embodiment of the invention, the winding drum W is provided in its periphery and preferably adjacent to an end flange 52 thereof with a circumferentially disposed slot 53 extending about one-fourth the way around the drum. This slot 53 gradually increases in depth from one end toward the other whereby one end of the slot provides a shoulder 54 disposed substantially radial of the drum W. As is clearly illustrated in Figure 5, the bottom wall of this slot 53 is disposed on such a curvature as to allow the inner or connected extremity of the cable to effectively wind on the drum and in a manner whereby the attachment of the cable to the drum will in no way afford any hindrance or obstruction to the desired effective winding of the cable.

As is shown in Figure 5, one extremity of the cable or flexible member F is threaded through an opening 55 disposed through the peripheral portion of the drum W beyond the shoulder 54

and at the bottom of such shoulder. This opening 55 as herein disclosed is also substantially at right angles to the shoulder 54.

The outer portion of the shoulder 55 is enlarged as at 56 by an outward taper whereby a suitable tapered sleeve head may be applied to the extremity of the cable F and so fits within the enlarged portion 56 to assure the desired effective maintenance of the securement of the flexible member F to the drum W.

Rotatably supported between the side members 1 of the body B in advance of the drum D is a roller 57 with which the cable engages to assure desired travel of the cable C relative to the body B.

It is also to be stated that the plate 48 which is carried by the flange 47 of the clamp A serves as a safety measure or guard to protect the hand particularly when applying the clamp to barbed wire.

It is also to be stated that the shafts 19, 27, 36 and 57 have their extremities which are directed through the side members 1 reduced so that the intermediate portion of each of said shafts 19, 27, 36 and 57 serves as a medium to maintain the side members 1 of the body B in perfect alignment.

From the foregoing description it is thought to be obvious that a pulling device constructed in accordance with my invention is particularly well adapted for use by reason of the convenience and facility with which it may be assembled and operated.

I claim:

1. A pulling device comprising an elongated body including a pair of frame members juxtaposed at their respective ends and spaced apart in parallel relation at an intermediate portion thereof, the members diverging between the ends and intermediate portion, means securing the members together at the respective ends, a drum rotatably supported between the members at the intermediate portion, means for intermittently rotating the drum, a cable adapted to wind on the drum and a guard member extending part way around the drum for limiting outward movement of the cable, the ends of the guard being secured to the body by cross members extending between the frame members.

2. A pulling device comprising an elongated body including a pair of frame members juxtaposed at one end and spaced apart in parallel relation at an intermediate portion thereof, the members diverging between said one end and the intermediate portion, means for securing the members together at said one end, a drum rotatably supported between the members at the intermediate portion, a cable adapted to wind on the drum, means for intermittently rotating the drum to wind the cable thereon, means for holding the drum against retrograde movement, a two-part member having a portion secured to said one end by said means for securing the members together at said one end, and having a portion extending therebeyond, the extending portion having recess means therein, a shank mounted to swivel about the longitudinal axis of the body having means thereon seated in the

recess for preventing separation of the shank and two-part member, a clevis at one end of said shank, and at least one hook member projecting laterally of the shank.

3. A pulling device comprising an elongated body including a pair of frame members juxtaposed at one end and spaced apart in parallel relation at an intermediate portion thereof, the members diverging between said one end and the intermediate portion, means for securing the members together at said one end, a drum rotatably supported between the members at the intermediate portion, a cable adapted to wind on the drum, means for intermittently rotating the drum to wind the cable thereon, means for holding the drum against retrograde movement, a two-part member having a portion secured to said one end by said means for securing the members together at said one end, and having a portion extending therebeyond, the extending portion having recess means therein, a shank mounted to swivel about the longitudinal axis of the body having means thereon seated in the recess for preventing separation of the shank and two-part member, a clevis at one end of said shank, and a pair of hooks projecting laterally in opposite directions from the shank.

4. A pulling device comprising an elongated body including a pair of frame members juxtaposed at their respective ends and spaced apart in parallel relation at an intermediate portion thereof, the members diverging between the ends and intermediate portion, means securing the members together at the respective ends, a drum rotatably supported between the members at the intermediate portion, the drum having flanges at the sides thereof, means for intermittently rotating the drum, a cable adapted to wind on the drum, and a guard member extending part way around the drum for limiting outward movement of the cable, the guard member comprising a strip of metal of a width to be disposed between said flanges and having ends engaging cross members extending between the frame members for securing it to the body.
